AUTOMOBILE CIGARETTE LIGHT QUENCHER AND ASHTRAY

Frank F. Magdziarz, Calumet City, Ill.

Application August 26, 1957, Serial No. 680,336

3 Claims. (Cl. 131—237)

This invention relates to ash receivers and more particularly to a device for automatically quenching ignited cigarettes and discharging them into an ash receiver.

It is an object of the present invention to provide a cigarette quencher for use with ash trays carried within automotive vehicles so as to facilitate the extinguishing of the cigarettes before they are dropped into the ash receptacle so as to minimize the possibility of fires and eliminate the necessity of having to open unsightly ash receptacles within the vehicle.

A further object of the present invention is to provide a cigarette quencher of the above type that may be readily mounted upon substantially any type of ash tray in which the cigarettes may be extinguished without soiling the hands, discharging ashes into the ambient air, and without requiring the use of more than one hand for the entire operation.

For other objects and for a better understanding of the invention, reference may be had to the following detailed description taken in conjunction with the accompanying drawing, in which:

Figure 1 is top plan view, with parts broken away, of a cigarette quencher made in accordance with the present invention in operative use;

Figure 2 is a side elevational view of the device shown in Figure 1;

Figure 3 is a front elevational view of the apparatus shown in Figure 2;

Figure 4 is an enlarged fragmentary cross sectional view showing details of certain parts of the present invention;

Figure 5 is a perspective view of another operating part of the present invention; and

Figure 6 is a front plan view of a still further element forming a part of the present invention.

Referring now more in detail to the drawing, a cigarette quencher 10 made in accordance with the present invention is shown in operative association supported upon the top of an open top ash tray 13. This device includes a cover plate 12 which supports all of the operating parts so that the device can be readily removed from the ash tray in order to empty the contents of the ash tray during use.

This ash tray 13 includes a front panel 15 that has a knob 14 for effecting reciprocating sliding movement thereof in a conventional manner. The front panel 15 also defines a transverse slot 16, through which an operator extension 23 extends for purposes hereinafter described. The actual operating mechanism includes an operating lever 17 that has a substantially centrally located pressure plate 18. This lever 17 is provided with an ear 20 at one end which is pivotally secured to the cover plate 12 by means of a rivet 21. A leaf spring 24 secured to one of the side walls of the cover plate 12 normally urges the pressure plate 18 of the operating lever 17 toward the opposite side wall of the ash tray 13. However, a resilient latch hook 26 yieldably mounted upon the one side wall of the cover plate 12

2

extends through an aperture 27 in the pressure plate 18 to retain the operating lever in the retracted position. A manually operated actuator in the form of a frame 30 having a central opening 31 overlies the top of the cover plate 12 and is supported, by means of depending lugs 32 which are slidably received within provided openings in the cover plate 12, for limited vertical movement. These lugs 32 are positioned at three corners of the rectangular frame 30, while the remaining corner includes a downwardly extending leg 33 that rests upon the top of the hook finger 26, as is more clearly shown in Figure 4.

In actual use, the cover plate 12 and operating parts carried thereby are placed upon the top of the ash tray 13 and the operator extension 23 which extends through the slot 16 is moved against the action of the spring 24 into engagement with the hook finger 26 which secures the pressure plate in the retracted position 18a out of engagement with the opposite side wall of the ash tray. When it is desired to extinguish a cigarette, it is extended downwardly through the opening 31 in the actuator frame 30 and into a similar opening in the cover plate 12 so that it is disposed in the path of movement of the operating lever. By then depressing the actuator frame 30, the leg 33 is operative to depress the latch hook 26 to the release position 26a, whereupon the pressure plate 18 will move, under action of the leaf spring 24, toward the opposite side wall of the ash tray under the action of the leaf spring 24 to squeeze the cigarette 35 between the pressure plate 18 and the side wall of the ashtray, thus extinguishing the lit end. The parts may then remain in this position until the next cigarette is to be extinguished, prior to which the operator extension 23 is returned to the initial position 23a where it is held by the hook finger 26, until the next cigarette is to be extinguished. It is noted that the slot 16 in the front panel 15 has a length sufficient to permit the lever 17 to pivot to such an extent that the pressure plate 18 will clamp the lit end of a cigarette against the adjacent side wall in order to extinguish the same. When the extension 23 is moved to the position 23a, the extinguished butt will drop into the ash tray 13. After the ash tray has become filled, it is only necessary to raise the cover plate 12 from engagement therewith whereupon the ash tray 13 may be moved longitudinally out of its mounting, emptied, and returned into operative association with the quencher.

While various changes may be made in the detail construction, it shall be understood that such changes shall be within the spirit and scope of the present invention as defined by the appended claims.

What I claim as new and desire to protect by Letters Patent of the United States is:

1. A cigarette quencher comprising, in combination, a mounting plate to be removably supported upon the open top of a slidably mounted ashtray receiver having spaced parallel side walls, an operating lever pivotally supported at one end upon said mounting plate for movement in a plane parallel thereto and having an opposite end extending outwardly of the tray, a pressure plate carried by said operating lever, spring means urging said pressure plate toward one of said side walls of said ash receiver, releasable means restraining said pressure plate when out of engagement with said one side wall, and a manually operated actuator for operating said releasable means to permit said pressure plate to move toward said one side wall to squeeze a cigarette between said pressure plate and said one side wall, said releasable means comprising a resilient latch mounted upon the lower side of said mounting plate, and said actuator comprising a frame mounted upon the top of said mounting plate having a depending leg in abutting engagement

with said latch for effecting movement thereof toward an open position.

2. The combination according to claim 1, wherein said mounting plate includes an aperture for receiving said leg therethrough.

3. The combination according to claim 2, wherein said spring means comprises a leaf spring acting between said operating lever and the other one of said side walls.
